BY

E. H. Bond

ATTORNEY

UNITED STATES PATENT OFFICE.

JAMES M. WILLS, OF OTTAWA, ONTARIO, CANADA.

LIFTING JACK.

Application filed March 16, 1922. Serial No. 544,381.

To all whom it may concern:

Be it known that I, JAMES M. WILLS, a citizen of the Dominion of Canada, residing at Ottawa, in the county of Carleton and Province of Ontario, have invented certain new and useful Improvements in Lifting Jacks, of which the following is a specification.

This invention has relation to certain new and useful improvements in a lifting jack which will be self lubricating and in which will be included double acting adjusting means controlled by an operating handle.

This invention has for another object the provision of a lifting jack of the character stated which will be of simple and comparatively inexpensive construction and in which the lifting screw will have an independent spiral movement within the spirally movable sleeve during the adjustment of the parts of the device when in engagement with a stationary object; the lifting screw moving with the sleeve when the lifting screw is not engaged with a stationary object to prevent rotation of the lifting screw.

The invention has for a further object the provision of a lifting screw of the character stated which will be of compact form as well as highly efficient in use and which may be readily and accurately adjusted and operated.

The invention has for a still further object the provision of a lifting jack of the character set forth which will be composed of the minimum number of parts and may be readily assembled as well as highly efficient in use.

With the foregoing and other objects in view as will be apparent as the description proceeds the invention consists in the novel construction, combination and arrangement of co-operating elements as hereinafter more specifically set forth, claimed and shown in the accompanying drawings forming a part of the present application and in which:

Figure 1 is an elevation of the complete device.

Figure 2 is a plan view of the lifting jack.

Figure 3 is a transverse section on the plane of line 3—3 of Figure 1, looking in the direction indicated by the arrows.

Figure 4 is a vertical sectional view sub-

stantially on the plane of line 4—4 of Figure 2, looking in the direction indicated by the arrows.

Referring more in detail to the drawings in which similar reference characters designate corresponding parts throughout the several views, 3 indicates the body casting having a vertical central opening 4 which is threaded in its upper portion to receive the exteriorly threaded lifting sleeve 5, as shown clearly in Figure 5. The lower end 6 of the casting 3 is reduced and exteriorly threaded to receive the base cap 7 which is also illustrated in Figure 4. The lifting sleeve 5 is also interiorly threaded in its upper portion to receive the threaded lifting screw 8 which carries the work receiving member 9 on its upper end. It will be seen that a lubricant may be placed in the lower end of the central opening 4 of the body casting 3 to lubricate the lifting sleeve 5 and the lifting screw 8 as they are lowered. The cutting away of the threads at the lower ends of the central opening 4 of the body casting 3 and the lower portion of the bore of the lifting sleeve 5 will permit a proper lubrication of these parts.

The body casting 3 has a pocket 10 in its upper end opening on the top and the opposite sides of the body casting 3. A collar 11 extends upwardly in the center of the pocket 10 around the lifting sleeve 5 and a bearing member 12 seats upon the collar 11. The second bearing member 13 is spaced above the member 12 and the bearing balls 14 are located between the bearing members 12 and 13. A bevel gear 15 seats upon the bearing member 13 and the collar 16 of the bevel gear 15 extends upwardly into the apertured cap 17. The apertured cap 17 is positioned around the lifting sleeve 5 and is employed for closing the upper end of the pocket 10. The apertured cap 17 has a dependent flange 18 threaded in the upper end of the body casting 3, as shown in Figure 4. The bevel gear 15 has a lug 19 projecting into its central opening for engagement in the longitudinal slot 5' extending on the outer side of the lifting sleeve 5 to cause rotation of this sleeve when the gear 15 is rotated.

As means for operating the bevel gear 15, an operating bevel gear 20 is employed and positioned in one of the side extensions of the pocket 10. This operating bevel gear 20 is in mesh with the bevel gear 15 to rotate

the latter. A stem 21 projects from one face of the operating bevel gear 20, through a sleeve 22 and the plug 23 is formed on one end of the sleeve 22. This plug is threaded 5 in the side extension of the pocket 10. An adjustable handle bar 24 is provided with an elongated slot 25 through which the outer end of the stem 21 may project, the portion 10 of the stem 21 receiving the slot 25 being preferably squared so that rotation of the handle bar 24 will cause a similar rotation 15 of the stem 21 and the bevel gear 20. Suitable washers 27 may be placed on opposite sides of the slotted central portion of the handle bar 24 and a thumb nut 28 or the like may be mounted on the threaded outer extremity of the stem 21 to retain the handle bar 24 in adjusted position upon the stem 21. Suitable handle members such as hand 20 grips 30 are carried on the pins 31 projecting laterally from the end portion of the handle bar 24. It is evident that the handle bar 24 may be readily moved or adjusted back and forth on the stem 21 to move either 25 handle members 31 away from the stem 21, as may be desired to increase or decrease the leverage. The opposite end extension of the pocket 10 may be closed by the threaded block 32 forming a removable closure for 30 that end of the pocket as shown in the drawing.

It is believed the complete construction and operation should now be apparent to parties familiar with this art from the foregoing paragraphs taken in connection with the accompanying drawings, without further detailed description. It may be briefly stated, however, that when the operating handle (including the handle bar 24 and handle grips 30) is turned in one direction, the lifting sleeve 5 will be caused to rotate so as to work upwardly out of the body casting 3. When the operating handle is turned in the reverse direction, however, the lifting sleeve 5 is caused to rotate in the reverse direction and travel downwardly in the body casting 3. The motion is imparted from the handle bar 24 and the stem 21 and the operating bevel gear 20 mounted thereon to the bevel gear 15 and this readily causes operation of the lifting sleeve 5. When there is a pressure upon the lifting screw 8, this member is prevented from rotating and, therefore, moves longitudinally in the lifting sleeve 5. When the block 9 on the lifting screw 8 is in engagement with any stationary object or is held against rotation, the lifting sleeve 5 will rotate on the lifting screw 8. The lifting sleeve 5 must at all 55 times rotate in the threaded opening 4 of the

body casting 3 when the operating bevel gear 15 is rotated and in the same direction with the operating bevel gear 15. As the lifting sleeve 5 rotates with the operating bevel gear 15 the lifting sleeve 5 also moves longitudinally through this operating bevel gear 15. The slot 5 ends a short distance from the bottom of the sleeve 5, so as to act as a stop when the sleeve is rotated to the desired limit. It is believed that further detailed 65 description is unnecessary. The pocket 10 serves as a reservoir for lubricant and the closure 32 serves to keep the same liquid-tight and provides for replenishing the lubricant when necessary, and for access to 70 the ball bearings, etc.

While the preferred embodiment of this invention is shown and described, it is to be understood that minor changes in the details of construction and arrangement of parts 80 may be resorted to within the scope of what is claimed without departing from the spirit of the invention.

What I claim as new is:

1. In a lifting jack, a body member, an 85 exteriorly-threaded lifting sleeve having threaded engagement therein and interiorly threaded, a threaded lifting screw engaged therein and having independent spiral movement therein during the adjustment of the parts in operation and movable with the sleeve when the screw is not engaged with a stationary object, means for rotating the lifting sleeve to move the same upwardly, and means embodying an operating bevel gear 95 rotating with said sleeve and through which said sleeve moves.

2. In a lifting jack, a body member, an exteriorly-threaded lifting sleeve having threaded engagement therein and interiorly threaded, a threaded lifting screw engaged 100 therein and having independent spiral movement therein during the adjustment of the parts in operation and movable with the sleeve when the screw is not engaged with a stationary object, means for rotating the lifting sleeve to move the same upwardly, and means embodying an operating bevel gear 105 rotating with said sleeve and through which said sleeve moves, said sleeve having a slot terminating near the bottom thereof to 110 serve as a stop when the sleeve has rotated to a desired limit.

In testimony whereof, I affix my signature in the presence of two witnesses.

JAMES M. WILLS.
